UNITED STATES PATENT OFFICE.

EMANUEL A. REICH, OF WHEELING, WEST VIRGINIA.

SIDEWALK-LIGHT.

No. 849,020.

Specification of Letters Patent.

Patented April 2, 1907.

Application filed November 19, 1906. Serial No. 343,963.

To all whom it may concern:

Be it known that I, EMANUEL A. REICH, a citizen of the United States of America, and a resident of Wheeling, county of Ohio, and 5 State of West Virginia, have invented certain new and useful Improvements in Sidewalk-Lights, of which the following is a specification.

My invention relates to new and useful 10 improvements in sidewalk-lights, and more particularly to a frame for sidewalk-lights.

An object of the invention is to provide a simple, durable, and inexpensive supporting-frame for the glass lights employed in 15 sidewalks for admitting light to basements, cellars, &c.

A further object is to provide a supporting-frame for sidewalk-lights which may be shipped knocked down and which is readily 20 set up in place.

A still further object is to provide a frame 25 of the character mentioned the supporting-bars of which are provided with spaced lugs which are adapted to engage and firmly lock in position on said bars the cross or light-holding bars, said lugs forming guides for the placing of the said cross-bars, rendering it possible for any unskilled mechanic to properly assemble the parts of the frame; and a 30 still further object is to provide a supporting-frame for sidewalk-lights which is readily applicable to other than rectangular openings—that is, to any quadrilateral opening or space.

35 With these and other objects in view the invention finally consists in the particular construction, arrangement, and combination of parts which will hereinafter be fully described, reference being herein had to the accompanying drawings, forming a part of this 40 specification, in which—

Figure 1 is a fragmentary top plan view of a portion of a sidewalk-light embodying my invention. Fig. 2 is an enlarged cross-section of a portion of the same. Fig. 3 is a perspective view of a portion of the supporting bar or table. Fig. 4 is top plan view of the table; and Fig. 5 is a top plan view of a portion of the frame, showing the bars 45 mounted for fitting a non-rectangular opening or space.

50 Referring to said drawings, in which like reference - numerals designate like parts throughout the several views, 1 indicates 55 supporting-bars of T shape adapted to be

suitably mounted across the sidewalk-opening, said bars being adapted to be spaced apart according to the relative strength thereof and the weight they are intended to sustain. Said bars are mounted with the 60 table portions 2 thereof uppermost and with the stems 3 extending vertically downward, as shown. In the tables 2 to one side of the stem 3 are struck-up lugs 4, adapted to overlie the base-flanges 5 of T-shaped bars 6. 65 Said bars 6 are mounted transversely of the bars 1 upon the table portions of the latter, with their stems 7 standing upright, and are adapted for supporting upon their base-flanges 5 the opposite ends of glass lights 8. The lugs 4 are adapted to closely overlie said base-flanges 5 to firmly hold the bars 6 in position on the bars 1, and they are spaced to hold the bars 6 the required distance apart for supporting the lights 8.

75 The stem 7 of each bar 6 is made narrow and short—narrow to allow a large space to intervene between said stem and the bodies of the glass lights 8 for holding a body 10, of cement, while the bases 9 of said lights lie 80 closely against the base of the stem, firmly holding the bars 6 in interlocking engagement with the lugs 4 of the bars 1, and short to admit of the cement closing over the top of the stem without rising above the level of 85 the lights 8.

All the lugs 4 in each bar 1 preferably extend in the same direction with the exception of the last lug on the end of the bar toward which the plurality of lugs are directed, 90 which one lug is extended in the reverse direction. The object of this arrangement of the lugs is to provide supporting means for the bars 6 when the frame is mounted in an inclined position. In such case the bars 1 95 are laid on the incline, with the plurality of lugs directed upward along the incline and the one directed downward. The lugs 4 are also preferably staggered, alternate lugs being struck up in the table portion 2 on opposite sides of the stem 3. The strain on said table is therefore equally divided between the opposite edges or flanges thereof.

Having thus described my invention, what I claim as new, and desire to secure by Letters Patent, is—

1. In a knockdown frame for sidewalk-lights, T - shaped supporting - bars, spaced lugs struck up from the table portions of said bars, and inverted-T-shaped bars mounted 110

transversely of the first-mentioned bars with their base-flanges underlying the points of said lugs.

2. In a knockdown frame for sidewalk-lights, **T**-shaped supporting-bars, lugs struck up from the table portions of said bars, and inverted - **T** - shaped bars mounted transversely of the first-mentioned bars on the table portions thereof, the said lugs serving as 10 spacers for the mounting of said inverted bars and adapted for holding said bars in upright positions.

3. In a knockdown frame for sidewalk-lights, **T**-shaped supporting-bars, lugs struck up from the table portions of said bars, and inverted - **T** - shaped bars mounted transversely of the first-mentioned bars on the table portions thereof, the last-mentioned bars having stems relatively shorter in length 15 than the thickness of the light to be carried thereby, and the lugs of the first-mentioned bars in clamping engagement with the bases of the last-mentioned bars.

4. In a knockdown frame for sidewalk-lights, **T**-shaped supporting-bars, **T**-shaped bars mounted in inverted position transversely of the first-mentioned bars on the table portions of the latter, and lugs struck up at spaced intervals in said table portions, 20 said lugs being spaced according to the length of the glass lights to be supported and being in clamping engagement with the inverted bars whereby when said lights are mounted upon the last-mentioned bars the latter are 25 locked against lateral movement.

5. In a knockdown frame for sidewalk-lights, **T**-shaped supporting-bars, **T**-shaped bars mounted in inverted position transversely of the first-mentioned bars on the table portions of the latter, and lugs struck up 40 at spaced intervals in said table portions, said lugs being spaced according to the length of the glass lights to be supported by said last-mentioned bars and being in clamping engagement with said last-mentioned bars 45 whereby when said lights are mounted in the frame said last-mentioned bars are locked against lateral movement, the lugs of each table portion being all extended in the same direction with the exception of the lug at the 50 end toward which the plurality of lugs are directed, which lug is reversely directed.

6. In a frame for sidewalk-lights, supporting bars or tables, **T**-shaped bars mounted in inverted position transversely of said tables, lugs struck up at spaced intervals in the faces of said tables, said lugs being in clamping engagement with the base-flanges of said bars, said base-flanges serving as supports for the opposite ends of glass lights, said lugs 55 and said glass lights coacting to hold said bars against lateral movement, said bars having stems of less length than the thickness of the lights carried by the bars.

In testimony whereof I affix my signature 60 in presence of two subscribing witnesses.

EMANUEL A. REICH.
